DIAPHRAGM FOR SOUND-REPRODUCING MACHINES

Application filed May 22, 1925. Serial No. 32,181.

This invention relates to diaphragms for sound reproducing machines, and has for one of its principal objects the provision of a diaphragm which may be employed in connection with standard makes of machines, and which will aid substantially in the clear reproduction of sound.

Another and equally important object of the invention is to provide a diaphragm which will reproduce the recorded sounds without artificial, metallic, rasping, or other objectionable noises usually present in sound reproducing machines.

A further object is to provide a diaphragm of the character specified which is durable, of highly simplified construction, and cheap to manufacture.

Other objects and advantages will be apparent during the course of the following description.

In the accompanying drawings forming a part of this application, and in which like numerals are employed to designate like parts throughout the same—

Fig. 1 is a perspective view of the improved diaphragm.

Fig. 2 is a sectional perspective of the same.

In the drawings wherein for the purpose of illustration is shown a preferred embodiment of the invention, the numeral 5 designates the improved diaphragm, which as illustrated in Fig. 1 is in the nature of a disc-shaped body having a marginal rim 6. The body of the diaphragm is gradually and uniformly decreased in thickness from the axis thereof to the marginal rim 6 so as to produce a highly sensitive structure, and one which will not set up objectionable foreign noises.

Particular attention is directed to the fact that the web or central portion of the body of the diaphragm is of approximately the same thickness as the marginal rim 6, and that the edge portion of the web, or that portion of the web which joins the marginal rim is approximately one-half as thick as the rim. This provides an attaching portion of the necessary strength without making the web unnecessarily thick at the point where the necessary movement takes place.

In the manufacture of the improved dia-

phragm, I employ a composition of hard fiber and chamois skin, and grind the same together into a single mixture. This hard fiber may be in the form of wood pulp. The mixed fiber and chamois skin are now compressed into the form of a hard sheet in a heavy duty press, and are then cut into the form of discs. The discs are treated with benzol and aniline dyes, and are then put in another press and pressed into the shape illustrated in the drawing.

Finally, the diaphragm is coated with shellac and polished. It is believed to be well known that the shellac coating preserves and prolongs the life of the diaphragm.

It is believed to be obvious that the improved diaphragm may be easily mounted in the usual manner, and in use will reproduce the recorded sounds without setting up objectionable sympathetic noises.

The discs are first treated with benzol so that they will be rendered more flexible and are subsequently treated with aniline dye which give the disc a color and fill up any pores that may be present therein.

Having thus described the invention, what is claimed is:

1. A diaphragm consisting of a compressed mixture of hard fiber and chamois skin.
2. A diaphragm consisting of a compressed mixture of hard fiber and chamois skin, and said diaphragm being coated with shellac.

In testimony whereof I affix my signature.

ALEXANDER E. SQUYARS.
